UNITED STATES PATENT OFFICE.

OSCAR KATZENBERGER, OF CHICAGO, ILLINOIS.

DOOR-SPRING.

1,249,111.

Specification of Letters Patent.

Patented Dec. 4, 1917.

Application filed July 22, 1916. Serial No. 110,672.

To all whom it may concern:

Be it known that I, OSCAR KATZENBERGER, a citizen of the United States, and a resident of Chicago, in the county of Cook and State 5 of Illinois, have invented a new and Improved Door-Spring, of which the following is a full, clear, and exact description.

This invention relates to door springs and has for an object the provision of an improved construction whereby a spring may 10 be wound but cannot be wound to an undesirable extent.

A further object more specifically is the provision of a winding member for a door 15 spring and a stop or lug projecting therefrom for limiting the rotary movement thereof.

In the accompanying drawings:—

Figure 1 is a plan view of a spring shown 20 in position, the same disclosing an embodiment of the invention.

Fig. 2 is a sectional view through Fig. 1 on line 2—2, the same being on an enlarged scale with certain parts broken away.

Referring to the accompanying drawing by numerals, 1 indicates a door frame of any desired kind and 2 a door, the frame 1 having a plate 3 secured thereto in any suitable manner to which one end of a spring 4 is secured, the opposite end being secured to the extension 5 of the winding plate 6. The extension 5 projects through the upstanding wall 7 of a bracket 8 rigidly secured in any suitable manner to door 2. In this class of 35 door springs it is usually arranged to apply the spring and then wind the spring after it has been applied so as to produce the desired tension. Heretofore this winding might be done to any desired extent but oftentimes 40 the spring was wound until it broke. According to the present invention the winding plate 6 is provided with the usual apertures 9 for receiving the pin 10, which pin in operation rests on the stop 11. A rod or instrument of any kind may be placed in any 45 of the apertures 9 and the plate wound to

the desired extent, after which the pin 10 is placed in position for preventing unwinding and also for causing the transmission of tension from the spring to the brackets 8 50 and from thence to door 2.

In case a person attempts to wind the spring for too great a distance the lug or projection 12 will strike against the bracket 8, as shown in dotted lines in Fig. 2, and thus 55 limit the winding action. The lug 12 may be formed integral with the plate 6 or may be made separate and rigidly secured thereto in any desired way. It will be observed that the lug 12 will not in any way interfere with 60 the winding of the spring but will prevent the spring from being wound beyond an undesirable extent. In addition to preventing the spring being over-tensioned, the same feature embodied on the tension lug 65 also prevents the spring from being wound in the wrong direction, or, rather, unwound.

What I claim is:

A door spring, comprising two brackets, one of the brackets having an apertured 70 member, and provided with a stop adjacent said member, a plate-like winding member having a cylindrical projection extending through and turning in the aperture of the member of the bracket, said winding member being adjacent the apertured member and provided with radial apertures and a radial lug, said lug lying in the plane of said member and adapted when the said member is turned in one direction to engage 75 the bracket and to engage the stop when said member is turned in the opposite direction, a spring secured to one bracket and to the extension of the winding member, and a pin in an aperture of the winding member and 80 engaging the stop of the bracket, whereby the spring is prevented from being over-tensioned or wound in the wrong direction.

OSCAR KATZENBERGER.
